(57) **CLAIM**

The ornamental design for a rocking toy, as shown and described.

DESCRIPTION

FIG. 1 is a perspective view of a first embodiment of a rocking toy showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plane view thereof;

FIG. 7 is a bottom plane view thereof;

FIG. 8 is another perspective view of the rocking toy of FIG. 1 showing a child thereon;

FIG. 9 is perspective view of a second embodiment of a rocking toy showing my new design;

FIG. 10 is a front elevation view thereof;

FIG. 11 is a rear elevation view thereof;

FIG. 12 is a left side elevation view thereof;

FIG. 13 is a right side elevation view thereof;

FIG. 14 is a top plane view thereof; and,

FIG. 15 is a bottom plane view thereof.

The broken lines in the drawings depict environmental subject matter and form no part of the claimed design.

1 Claim, 15 Drawing Sheets
